JOSEPH P. HEENEY, OF EAST ST. LOUIS, ILLINOIS, ASSIGNOR TO M. H. FOUNDRY AND MANUFACTURING COMPANY, OF BELLEVILLE, ILLINOIS, A CORPORATION OF ILLINOIS.

DRINKING-FAUCET.

979,489.

Specification of Letters Patent. Patented Dec. 27, 1910.

Application filed August 1, 1910. Serial No. 574,940.

To all whom it may concern:

Be it known that I, JOSEPH P. HEENEY, citizen of the United States, residing at East St. Louis, in the county of St. Clair and State of Illinois, have invented certain new and useful Improvements in Drinking-Faucets, of which the following is a full, clear, and exact description, reference being had to the accompanying drawings, forming 10 a part hereof.

My invention has relation to improvements in drinking faucets; and it consists in the novel details of construction more fully set forth in the specification and pointed out in the claims.

In the drawings, Figure 1 is a perspective of a bowl showing my invention applied thereto; Fig. 2 is an enlarged combined longitudinal section and elevation of the faucet; Fig. 3 is a top plan of the faucet; Fig. 4 is a sectional detail on the line 4—4 of Fig. 2; Fig. 5 is a middle longitudinal section of the inner valve-casing or hollow post showing the screw-valve therein; and Fig. 6 is a 25 cross-section on the line 6—6 of Fig. 5.

The object of my invention is to construct a hygienic drinking faucet (or bubbling cup) which shall project a stream of water beyond the body of the faucet (or cup) so 30 as to permit of drinking from said stream without the necessity of bringing the lips into contact with the faucet (or cup), and thus avoiding contamination with disease germs.

35 A further object is to provide a faucet (or cup) in which the integrity of the stream may be preserved for its full height, no spreading of the stream being possible.

A further object is to provide means with- 40 in the faucet (or cup) for regulating the height of the projected stream; for regulating the direction of its projection; for cutting off the stream for certain positions of the faucet to prevent abuse thereof by mischievous persons; to maintain a uniform flow under all pressures; and to effect further and other advantageous results better apparent from a detailed description of the invention, which is as follows:

50 Referring to the drawings, 1 represents a pipe-fitting mounted adjacent to a bowl B, and provided with the usual faucet valve V, well understood in the art. Leading from the pipe 1 is a hollow arm or pipe 2, the terminal walls of which are provided with op-

posite ports o, o', either of which may be brought into register with the passage-way or port o'' at the bottom of the faucet-cup 3 mounted rotatably about the outer end of the arm 2 directly over the ports o, o'. The 60 rotatable connection is effected by an ornamental arm 4 projecting from the base of the cup, said arm having a loop or hollow-boss 5 (adjacent to the open bottom of the cup), which slips over the pipe 2, being secured thereon by a screw-plug p, which screws into the open end of the pipe (2), a packing washer w being preferably interposed between the screw and boss 5. When the cup is turned up the ports o, o'' are 65 brought into register and water will flow into the cup; when the cup is turned vertically down, the ports o', o'', are brought into register when again the water flows into the cup, the latter in its inverted position being 70 capable of use as an ordinary faucet. When the cup is turned to a horizontal position, the several ports are out of register and the flow is cut off, thus preventing mischievous boys or other persons from directing the 75 stream against others and wetting them, and frustrating the plans of such persons to divert the cup from the legitimate purpose 80 which it is intended to subserve.

Screwed into the passage-way o'' within 85 the cup 3, is a hollow post 7 on which is formed an annular flange 8 at a suitable point beyond the base of the threads, said flange being spaced a suitable distance from the inner bottom wall of the cup so as to 90 leave an annular clearance a for the passage of the water into the cup, the water finding its way into the cup through a series of ports 9 formed in the walls of the post between the base of the screw-threaded portion and the flange 8. The upper edge of the post is preferably provided with diametrically opposite grooves or splits n for engagement with a split wrench or equivalent tool by which the post is driven home. 95 Operating in the hollow-post 7 is a screw-valve 10 (the post serving as a casing therefor), the bottom head 10' of the valve coming in proximity and opposite to, the ports 9, any shifting or longitudinal adjustment 100 of said valve directly affecting the freedom of flow of the water through said ports, the greatest constriction being produced when the center of the head 10' is in the transverse plane intersecting the centers of the 105 110

ports (Fig. 5 dotted position). Over the upper projecting end of the screw is passed a lock-nut 11, this end of the screw being preferably provided with a transverse split 5 or groove 12 for the application of a screw-driver so that adjustment of the screw-valve may be made from that end, and without the necessity of removing the post to make the necessary adjustment. The adjustment from the top may be made by 10 simply removing the screw-cap 13 by which the cup is kept closed, and inserting a screw-driver into the slit 12 of the screw or by inserting a small screw-driver through the opening 14 without removing the screw-cap. The screw-cap 13 is provided with a central 15 relatively large discharge opening 14 bounded by a series of smaller or constricted ports or openings 14' in close proximity thereto, the streams issuing from the ports 14' hugging the main stream issuing through the opening 14 and preventing the same from spreading and breaking, and hence preserving the integrity thereof. It follows 20 therefore that the composite or resultant stream S is solid and does not break, the free end of the same simply running back along the main body of the stream into the bowl B.

The operation of the faucet is substantially as follows:—Upon turning the main 25 faucet-valve V to open position, the water rushes to the end of the hollow arm 2; and, should the cup 3 be swung upward so as to bring the ports o, o' into register, the water 30 rushes into the hollow post 7 between the valve-head 10' and ports 9, through said ports 9 into and through the annular clearance a into the cup. From the cup it is projected through the opening 14 and ports 14' 35 with the results already specified, the final solid stream S allowing a height of substantially five or six inches. The person 40 may then plate his mouth over the end of the stream and drink without contacting with the cup. No matter what the driving head of the stream may be with a full open 45 position of the valve V, the height of the final stream may be carefully regulated and adjusted within the cup by simply adjusting 50 the screw-valve 10 in the manner indicated, such adjustment accurately determining the amount of clearance between the head 10' thereof and the ports 9 as obvious from the drawings. By turning or swinging the cup 55 vertically downward, the ports o, o', are brought into register and the stream S shoots downward, the cup subserving the purpose of an ordinary faucet. By swinging the cup to a horizontal position the several ports o, o', o'', are out of register and 60 no water is delivered, making it impossible for mischievous persons to use the cup for illegitimate purposes.

Having described my invention, what I claim is:—

65

1. In combination with a conduit leading from a source of water supply flowing under pressure, a cup coupled to said conduit and communicating therewith, said cup having a main discharge opening of relatively large 70 cross - sectional area, and supplemental smaller ports located adjacent to, and surrounding the main opening, the axes of the ports being disposed so as to direct the streams therefrom in substantial parallelism 75 to the stream from the main opening and thereby preserve the integrity thereof and prevent the same from spreading.

2. In combination with a conduit leading from a source of water supply flowing under 80 pressure, a cup coupled to said conduit and communicating therewith, said cup having a main discharge opening of relatively large cross - sectional area, and supplemental smaller ports located adjacent to, and surrounding the main opening, the axes of the ports being disposed so as to direct the streams therefrom in substantial parallelism 85 to the stream from the main opening, and thereby preserve the integrity thereof and 90 prevent the same from spreading, and means within the cup for regulating the height of the stream issuing from the cup.

3. A drinking faucet comprising a hollow member having an intake opening, a valve-casing in the hollow member communicating with said opening and provided with ports discharging the water from the point of intake into the chamber of the hollow member, a valve in said casing for regulating the flow 100 through the ports aforesaid, the walls of the hollow member being provided with discharge openings for the purpose set forth.

4. A drinking faucet comprising a hollow cup having a bottom intake opening for the 105 water, a hollow post secured in the cup around said opening and provided with an outer formation leaving an annular clearance between it and the inner walls of the cup, the post being provided with ports below said 110 formation, a reciprocating valve-piece mounted in the post and having one end operating across the plane in which the ports aforesaid are disposed, means for adjusting said valve-piece from a point within the cup, 115 and a removable top for the cup above the post and valve-piece, said top being provided with a main, and supplemental encompassing discharge ports for the purpose set forth.

In testimony whereof I affix my signature, in presence of two witnesses.

JOSEPH P. HEENEY.
